By A. L. Jackson Attorney

UNITED STATES PATENT OFFICE.

JOHN GALLATIN KEARBY, SR., AND WILLIAM HUBERT GOODNIGHT, OF DALLAS,
TEXAS; SAID GOODNIGHT ASSIGNEE TO SAID KEARBY.

VENDING MACHINE.

Application filed February 2, 1923. Serial No. 616,553.

Our invention relates to vending machines and more particularly to coin-operated vending machines for selling pencils and other articles of trade; and the object 5 is to provide machines which are simple in construction and simple in operation and which can be marketed at small cost. Another object is to provide machines which have all parts so arranged that they will 10 not be displaced in operation and which will operate with precision and which will positively deliver a pencil or other article whenever the proper coin is placed in the coin chute before operating the machine. Other objects and advantages will be fully 15 explained in the following description and the invention will be more particularly pointed out in the claims.

Reference is had to the accompanying 20 drawings which form a part of this application.

Fig. 1 is a front elevation of the machine with the front cover or casing omitted. Fig. 2 is a plan view with the casing for 25 the lower part omitted. Fig. 3 is a vertical section, taken on the lines 3—3 of Fig. 1. Fig. 4 is a perspective view of the coin-releasing device. Fig. 5 is a side elevation of the bar which forms the lower part of the partition between the two compartments. Fig. 6 is a longitudinal section of the lower part 10 of the casing.

Similar characters of reference are used 30 to indicate the same parts throughout the several views.

The machine is provided with a casing composed of a back member 1, a bottom 2, and a front member 3 which is removable and which incloses only the lower front 35 part. The machine is provided with a cabinet or compartment for containing the goods to be sold. This cabinet is formed on the back 1 which has integral side members 4 which are provided with inturned 40 flanges 5. On the front of the upper part of the cabinet, there is preferably a transparent removable plate 6 held in place by the flanges 5 and by screws 7 and by the bar 8. The transparent plate 6 covers the 45 front of the upper part of the cabinet and extends partly within the compartment 9. That part 10 of the front casing for the cabinet has a series of slots hereinafter explained and the part 10 has an integral part 50 11 bent under to form the bottom of the

goods cabinet. The compartment 9 for housing the operating mechanism has side casing members 12 and 13 and a removable cover 14 which is provided with depending flanges 15 for attaching the cover 14 to the sides 12 and 13 by means of bolts 16 and nuts 17. The cover 14 has a slot 18 for the coin and a slot for the handle 19. The coin chute 20 is rigid with the cover 14 and delivers the coin to the actuating mechanism.

The coin-actuating mechanism is located in the compartment 9. A bar 21 is supported on the side members 12 and 13 by depending flanges 22 and bolts 23. This bar 21 forms a part of the coin-actuating mechanism and supports the coin-actuating mechanism. The bar 21 has a slot 24 which is just wide enough to let the coin pass. The coin to be used generally is a nickel, 75 but it is apparent that the machine may be adapted to use any other suitable coin. The slot 24 registers with the chute 20 and receives the coin, but the coin is prevented from falling through the slot 24 by a yielding detent 25 which partly closes the passage at the bottom of the slot 24, and so the detent 25 holds the coin until the coin-actuating mechanism is moved. A slide 26 is mounted on and slides on the bar 21 and this slide is actuated by the handle 19 which is rigid with the slide. The slide 26 carries a coin releaser 27 which serves to release the coin when the handle 19 is actuated. The coin releaser 27 serves also as a lock to prevent the operation of the machine when there is no coin in the slot. The releaser 27 has a shoulder 28 and the detent 25 has a shoulder 29. If there is no coin in the slot 24, the handle 19 cannot be moved far enough to secure any goods. If the handle 19 is moved when there is no coin, the shoulder 28 would abut against the shoulder 29 and so stop the movement of the handle 19. The slide 26 has a slot 30 which registers with the coin chute 20 and the slot 24. When a coin is dropped in the chute 20, it will stop against the detent 25. When the handle 19 is moved, it will move the slide 26 and the upper edge of the slide 26 will press down on the coin at the point 31 and this pressure on top of the coin will exert pressure on the coin sufficient to depress the detent 25 and so release the coin. The detent 25 will be depressed until the shoulder 28 100

105 reaches the shoulder 28. The slide 26 has a slot 32 which registers with the slot 24. When the handle 19 is moved, it will move the slide 26 and the upper edge of the slide 26 will press down on the coin at the point 33 and this pressure on top of the coin will exert pressure on the coin sufficient to depress the detent 25 and so release the coin. The detent 25 will be depressed until the shoulder 28 110

passes the shoulder 29. Thus when there is a coin in the slot the shoulders 28 and 29 will not interfere with each other and the handle 19 can be actuated to deliver the goods. After the shoulder 28 passes the shoulder 29, the curved portion of the releaser 27 will ride on the shoulder 29 and so depress the detent 25. The detent 25 is pivotally mounted on the sides of the bar 21 by pivot studs 32 and a spring 33, which is attached to the underside of the bar 21, holds the detent up against the bottom of the bar 21 until it is depressed by the coin.

When the slide 26 is actuated the goods are delivered. The goods are stored in the cabinet 34. In illustration given, the cabinet 34 is adapted to contain lead pencils of the ordinary type, arranged one above the other. The slide 26 carries two pairs of posts 35 and 36 and these posts carry supporting arms 35' and 36' respectively. These supporting arms are adapted to project through slots 35'' and 36'', respectively, in the bar 10 which forms a part of the pencil cabinet. The bar 10 is partly grooved and partly slotted, the slots being formed in the bottom of the grooves. Normally the arms 35' project through the slots 35'' and support the column of pencils. While the arms 35' are supporting the pencils the arms 36' are resting in grooves 39 in the bar 10 and so are not projecting into the pencil column. Each arm 35' is operatively connected to each arm 36' by a wire 41 of each pair of arms. When the slide 26 is actuated by the handle 19, the arms 35' will commence to move out of the slots 35'' as soon as they strike the shoulders 37 of the grooves 38 and simultaneously the arms 36' will begin to slide out of the grooves 39 and commence to project through the slots 36'' and go on between the bottom pencil and the pencil above, the arms 36' being actuated by the arms 35'. The arms 36' will now support the column of pencils while the arms 35' are lying in the grooves 38, the bottom pencil having dropped from the arms 35' ready to be delivered through the door 45 in the bottom of the cabinet 34. The slide 26 carries an arm 42 which projects through a slot 43 in bar 10 for forcing the pencil out through door 45. The slide 26 is forced back to starting point by a spring 44 which may be attached to one of the posts 35 and to the side 13 of the compartment 9. When the slide 26 starts towards the starting point, the arms 35' will commence to move out of the grooves 38 into slots 35'' and arms 36' will simultaneously move and strike the shoulders 40 of grooves 39 and so begin to be forced out of slots 36'' and this operation continues until the arms 35' are again in position to catch the column of pencils just as the arms 36' release the column of pencils and the arms 36' then occupy the

grooves 39. In this latter operation, the arms 36' operate the arms 35' automatically by reason of the connection by the wires 41.

Various changes in the sizes, proportions, construction and arrangement of the several parts may be made without departing from our invention.

What we claim, is,—

1. A vending machine comprising a casing having a compartment for goods and a compartment for operating mechanism provided with a partition separating said compartments and provided with grooves and slots therein, main supporting arms projecting through slots in said partition for supporting the goods therein and supplemental supporting arms lying normally in grooves in said partition and adapted to project through slots therein and to support the goods when said main supporting arms are withdrawn from the goods department and are lying in grooves in said partition, and mechanism for actuating said arms.

2. A vending machine comprising a casing having a compartment for goods and a compartment for operating mechanism provided with a partition separating said compartments having grooves and slots therein, main supporting arms normally projecting through slots in said partition for supporting goods in said goods compartment and adapted to lie in grooves in said partition, supplemental supporting arms normally lying in grooves in said partition but adapted to project through slots in said partition for supporting goods while said main supporting arms are lying in grooves in said partition, means operatively connecting said main supporting arms and said supplemental supporting arms whereby said main supporting arms actuate said supplemental supporting arms, and mechanism in said operating compartment for actuating said main supporting arms.

3. A vending machine having a casing provided with a compartment for goods and a compartment for operating mechanism and a partition separating said compartments provided with slots and grooves therein, main supporting arms normally projecting through slots in said partition for supporting goods in said goods compartment and supplemental supporting arms normally lying in grooves in said partition but adapted to project through slots in said partition and to support goods when said main supporting arms are withdrawn therefrom and lying in grooves in said partition, means operatively connecting said main supporting arms and supplemental supporting arms whereby said main supporting arms actuate said supplemental supporting arms, mechanism in said operating compartment for actuating said main supporting arms, and an arm actuated by said mechanism projecting

from said operating compartment into said goods compartment for delivering goods therefrom.

4. A vending machine comprising a casing provided with a compartment for goods and a compartment for operating mechanism and a partition separating said compartments and provided with slots and grooves therein and the end walls of said grooves forming means for aiding in withdrawing supporting arms from said goods compartment, main supporting arms projecting normally through slots in said partition for supporting goods in said goods compartment but adapted to lie in grooves in said partition, supplemental arms normally lying in grooves in said partition but adapted to project through slots therein for supporting goods in said goods compartment when said main supporting arms are withdrawn therefrom and lying in grooves in said partition, means in said operating compartment for actuating said arms consisting of a slide operatively connected with said arms, and an arm actuated by said slide for delivering goods from said goods compartment.
5. A vending machine comprising a casing provided with a compartment for goods and a compartment for operating mechanism and a partition separating said compartments and provided with slots and grooves therein and the end walls of grooves in said partition forming co-operating means for withdrawing supporting arms from said goods compartment, main supporting arms normally projecting into said goods compartment for supporting goods therein but adapted to lie in grooves in said partition,

supplemental supporting arms normally lying in grooves in said partition but adapted to project through slots in said partition for supporting goods in said goods compartment when said main arms are withdrawn therefrom and are lying in grooves in said partition, a slide operatively connected with said arms and co-operating with said co-operating means for actuating said arms, an arm carried by said slide and projecting into said goods compartment for delivering goods therefrom, and a spring for restoring said slide to inoperative position.

6. A vending machine comprising a casing provided with a compartment for goods and a compartment for operating mechanism and a partition separating said compartments and provided with slots and grooves therein and the end walls of the grooves in said partition forming co-operating means for withdrawing supporting arms from said goods compartment, pairs of supporting arms adapted to project from said operating compartment into said goods compartment for alternate use in supporting goods therein, and a slide in said operating compartment operatively connected with said arms and co-operating with said co-operating means for alternatively projecting one pair of said arms at a time into said goods compartment and for projecting one pair of said arms into said goods compartment while the other pair is being withdrawn.

In testimony whereof we have signed our names to this specification.

JOHN GALLATIN KEARBY, SR.
WILLIAM HUBERT GOODNIGHT.

CERTIFICATE OF CORRECTION.

Patent No. 1,611,551, granted December 21, 1926.

to JOHN GALLATIN KEARBY, SR., ET AL,

It is hereby certified that the above mentioned patent was erroneously issued to John Gallatin Kearby, Sr., and William Hubert Goodnight, said Goodnight assignor to said Kearby, Sr., whereas said Patent should have been issued to J. G. Kearby Sales Corporation, of Orange, Texas, a Corporation of Texas, said Corporation being assignee by mesne assignments of the entire interest in said invention as shown by the records of assignments in this office; and that the said Letters Patent should be read with this correction therein that the same may conform to the record of the case in the Patent Office.

Signed and sealed this 8th day of February, A. D. 1927.

William A. Kinnan,
eal. Acting Commissioner of Patents.
